(57) **CLAIM**

The ornamental design for a transformer, as shown and described.

DESCRIPTION

FIG. 1 is a front view of a transformer showing our new design;

FIG. 2 is a rear view thereof;

FIG. 3 is a right side view thereof;

FIG. 4 is a left side view thereof;

FIG. 5 is a top plan view thereof;

FIG. 6 is a bottom plan view thereof;

FIG. 7 is a top perspective view thereof;

FIG. 8 is a cross-sectional view along line VIII-VIII of FIG. 7;

FIG. 9 is an exploded perspective view of the transformer of FIG. 7;

FIG. 10 is a bottom perspective view of the transformer of FIG. 1; and,

FIG. 11 is a right perspective view thereof.

The broken lines shown represent unclaimed subject matter and form no part of the claimed design.
